UNITED STATES PATENT OFFICE.

HENRY H. VAUGHAN, OF MONTREAL, QUEBEC, CANADA.

LOCOMOTIVE-BOILER AND STEAM-SUPERHEATER.

No. 863,333.

Specification of Letters Patent.

Patented Aug. 13, 1907.

Application filed November 5, 1906. Serial No. 342,100.

To all whom it may concern:

Be it known that I, HENRY H. VAUGHAN, a citizen of the United States, and a resident of Montreal, Quebec, Canada, have invented a certain new, useful, and Improved Locomotive-Boiler and Steam-Superheater, of which the following is a full, clear, and exact description, such as will enable others skilled in the art to which it appertains to make and use the same.

My invention relates to improvements in steam generators and has particular reference to improvements in locomotive boilers and improvements in superheaters for such boilers.

The particular objects of my invention are to improve the construction of locomotive boilers with a view to adapting the same for use with superheaters having a large number of superheating loops or tubes, which are located within the body portion of the boiler and to provide an efficient and durable steam superheater which shall be of simple construction and low cost.

Still further objects of my invention will appear hereinafter.

My invention consists generally in a locomotive boiler of the fire tube type, but which contains a superheater recess or chamber in its forward part and further my invention consists in a novel superheater particularly adapted for arrangement in the space thus provided.

My invention consists particularly in a superheater arranged within a large flue of the boiler and comprising a plurality of superheater loops or tubes, in combination with a plurality of saturate and superheated steam headers or passages arranged at the forward end of the boiler and connected respectively to the boiler dry pipe and the steam chests of the engines.

My invention also particularly consists in a locomotive boiler containing a large number of flues and also an enlarged superheater containing flue chamber or recess which is connected with the fire box by a plurality of short flues. And further my invention consists in novel means whereby the flow of gases in the enlarged flue or recess may be controlled.

My invention also consists in various novel constructions and in combinations of parts, all as hereinabove described and particularly pointed out in the claims.

The invention will be more readily understood by reference to the accompanying drawing and in which;

Figure 1 is a vertical longitudinal section on the line X—X of Fig. 2 illustrating a locomotive boiler, provided with a superheater, embodying my invention; Fig. 2 is a horizontal section on the line Y—Y of Fig. 1; Fig. 3 is an enlarged vertical section on the line Z—Z

of Fig. 1, the regulating damper being shown closed instead of open as in Fig. 1; Fig. 4 is a transverse vertical section on the line Z—U—Z of Fig. 1.

The locomotive boiler, A, which is shown in the drawings is, generally speaking, of a common type, but this boiler differs from all others in that it is provided with what I term a superheater recess or internal chamber or shell, B.

A¹ is the fire box flue sheet of the boiler, and A² is the forward or front end flue sheet. These flue sheets are connected by a large number of fire tubes or flues, A³.

C represents the smoke box containing the usual nozzle, D, petticoat pipes, D', and screen, E.

F represents the dry steam pipe of the boiler and G—G the steam feed pipes, which are connected with the engine steam chests (not shown) on opposite sides of the boiler.

The superheater hereinafter described is interposed between the dry pipe, F, and the pipes, G—G. The shell or cylinder, B, occupies the space usually occupied by the central fire tubes of a boiler and is arranged below the uppermost flues, A³, i. e. below the water line of the boiler. This shell constitutes an internal wall of the boiler and its open forward end is properly secured in the forward flue sheet, A². The shell is preferably corrugated to permit its expansion and contraction. It is shorter than the boiler, extending only part way back to the rear flue sheet, A¹. The rear end of the shell is closed by a small circular flue sheet, B¹ and the shell is connected with the fire box of the boiler by a plurality of short flues, A⁴, extending through the flue sheets, A¹ and B¹. It will be evident that the internal shell or cylinder constitutes and provides a cavity or recess within the forward part of the boiler and within this I arrange the major portion of the steam superheater. Said superheater comprises a plurality of steam ducts or members preferably all within a single metal casting, H, and a large number of small bent or return tubes or loops, H'. The body or group of tubes, H', substantially conforms to and trees the annular cylinder or recess and the casting, H, substantially closes the forward end of said recess. The tubes or loops, H', are relatively of less length than the cylinder, B, so that a considerable space, B², remains between the rear ends of the superheater pipes and the flue sheet, B¹. The hot gases from the fire box enter the superheater recess through the flues, A⁴, and flow forward therein to the smoke box. In this manner the superheating tubes are exposed to intense heat. The swiftly flowing hot gases from the flues, A⁴, lose much of their velocity within the large recess or superheater chamber through expansion. In consequence the flow of the hot gases through the body of superheating

tubes, H' , is relatively slow and both the walls of the recess and said tubes are therefore exposed to the heat of the gases for a greater length of time than would be tubes arranged within the long fire tubes of the boiler.

5 To further retard the flow of the gases and effectually equalize the temperature throughout the recess, I provide a number of forwardly inclined deflecting plates, I , within the shell, B . These plates also serve to support the superheater pipes, H^1 , in their proper positions, and may be attached either to said pipes or to the inner walls of the shell, B . The more convenient way is to secure the plates upon the tubes, when so attached the plates may be inserted and withdrawn with the superheater. As before stated the casting, H , which 15 contains steam passages, communicating with the superheating pipes, H' , occupies a position directly in front of the superheater recess or cavity and substantially closes the forward end thereof. To complete the closure, I employ a sheet metal cylinder, J , which joins 20 the member, H , to the flue sheet, A^2 . The lower part of the cylinder, J , is formed by a movable shutter or damper, J' , suitably hinged upon the flue sheet, A^2 and operable by means of a rock shaft, J^2 , provided with an operating arm, J^3 , on the exterior of the 25 smoke box or front end, C . This arm is arranged for operation in any suitable manner, as by a lever and rod extending from the locomotive cab, or by an automatic steam actuated mechanism connected with the steam chest of one of the engines. The provision of such 30 means for operating the damper, J' , is within the province of an ordinary mechanic, and hence I have deemed it unnecessary to illustrate the operating mechanism.

It will be obvious that when the damper, J , is open, as shown in Fig. 1, the flue gases may pass through the 35 superheater recess into the smoke box, while when the damper is closed the flow of hot gases through the superheater recess will be prevented as required, to prevent the burning of the superheating tubes, when the flow of steam therethrough is shut off. The tubes or 40 loops, H^1 , are of substantially uniform length and the tubes are straight throughout, except as it becomes necessary to bend their extreme forward ends to accommodate them to the connections or openings in the headers, H . The steam from the dry pipe, F , is distributed to the tubes, H' , by means of headers or passages, HL , and after being superheated therein the steam is collected in other passages from headers, HS , which latter communicate with the feed pipes, G . Each tube or loop, H' , has one of its ends connected 50 with a header, HL , and its other end connected with a header, HS , in this manner the body of steam from the boiler is minutely subdivided and absorbing heat from the extensive surfaces afforded by the many pipes or tubes, H' , is quickly raised to a high temperature.

55 Various steam distributing and collecting headers may be used in connection with the superheating tubes, H^1 , and if desired said headers may be separate or distinct parts, but I prefer to employ the structure shown in the drawings, comprising a single casting wherein 60 the necessary passages are formed. Referring to the drawings for the details of construction, it will be noted that the passages, HL and HS are vertical and are parallel, the same being distinguished by separating walls, H^3 . The lower ends of all the passages are 65 closed; the rear walls contain openings in which the

ends of the tubes, H' , are expanded or otherwise secured. The forward walls of the passages, HL and HS contain openings filled by plugs, H^4 , which being removed permit access to the ends of the tube through the headers. The upper part of the casting is a rearwardly turned elbow, H^5 , which joins the dry pipe, F , as shown in Fig. 1. This loop is connected with the tube passages, HL — HL by ducts, HL' (see Figs. 1 and 3); that portion of the member, H , directly beneath the elbow, H^5 , is formed into a cross portion, H^6 , terminating in forwardly turned elbows, H^7 , and containing a duct, HS' , which communicates with the upper ends of the three passages, HS (see Figs. 1, 3 and 4). The ends or loops, H^8 , of the member, H , are connected with the upper ends of the steam feed pipes, 80 G , as shown in Fig. 1.

The peculiar forms and disposition of the separating walls in the upper portion of the member H , will be clearly understood from Figs. 1 and 3. I prefer that the rear wall of the member, H , wherein the ends of 85 the tubes, H' , are secured shall be inclined downwardly and forwardly as represented in Fig. 1, with a view to the freer discharge of cinders, but it will be obvious that said rear wall may be parallel with the flue sheet, A^2 . In such cases I incline the forward wall of the 90 member, H , to preserve the tapered form of the passages, HL and HS , which tapered form is adapted for the purpose of equalizing the flow of steam to and from the superheating pipes, H' .

The operation of my superheater will be obvious from 95 the foregoing.

A peculiar advantage attaching to my structure arises through the leaving of the space between the rear ends of the superheater pipes and the end of the internal shell, whereby the said pipes or tubes are protected from the direct impact and intense heat of the fire box gases.

A further advantage accrues through the employment of the large shell or flue wherein the velocity of the gases is reduced so that a maximum of heat will be 105 imparted to the water in the boiler and to the superheating tubes.

It should be further noted that the structural convenience residing in the employment of the large internal shell is secured without materially depriving 110 the boiler of radiating surface and without disturbing the proper equalization of the flow of gases through all of the flues of the boiler.

The advantages attaching to the various details of construction, such for example as the grouping of the 115 superheating tubes in a single cavity or flue and the connection of said tubes with a single rigid member, which contains all of the steam distributing and collecting passages, are self-evident and need not be enlarged upon herein.

The peculiar means which I employ for closing the forward end of the superheater cavity and for controlling the flow of gases therethrough, possess the merit of simplicity and durability. I desire also to point out and it shall be understood that the boiler herein shown possesses distinct advantages apart from the superheater and providing the deflecting plates are arranged therein may be used to advantage without the superheater.

As various modifications of my invention will readily 130

suggest themselves to one skilled in the art, I do not confine my invention to the specific constructions herein shown and described.

Having thus described my invention, I claim as new and desire to secure by Letters Patent:

1. Improvements herein described, comprising a fire-tube boiler, its fire box and smoke box, in combination with a shell of less diameter than the boiler, the same extending from the front flue sheet part way to the rear flue sheet, a plurality of flues extending from said rear flue sheet into the rear end of said shell, saturate and superheated steam headers provided in said smoke box at the open end of said shell and a group of loop pipes occupying said shell and connected with said headers, substantially as described. 60
2. A locomotive fire-tube boiler, its fire box and smoke box, in combination with a shell of less diameter than the boiler, opening through the front flue sheet thereof and extending part way to the rear flue sheet, a plurality of flues 65 connecting the fire box and shell, a group of loop tubes or pipes occupying said shell and extending part way to the rear end of said shell, an open space remaining in the rear end of said shell and suitable saturate and superheated steam headers at the open end of said shell, within the 70 smoke-box of the boiler and connected with said pipes, substantially as described.
3. A locomotive fire-tube boiler, its fire box and smoke box, in combination with a shell of less diameter than the boiler, opening through the front flue sheet thereof and, 75 extending part way to the rear flue sheet, a plurality of flues connecting the fire box and shell, a group of loop tubes or pipes occupying said shell and extending part way to the rear end of said shell, an open space remaining in the rear end of said shell, suitable saturate and superheated steam headers in said smoke-box wherewith the forward ends of said pipes are connected with said pipes, and means in the smoke box for controlling the flow of fire box gases through said shell, substantially as described. 80
4. The improvements herein described, comprising a locomotive fire-tube boiler, its fire box and smoke box, in combination with a shell of less diameter than the boiler, opening through the front flue sheet thereof and extending part way to the rear flue sheet, a plurality of short flues 85 connecting the shell with the fire box, a group of superheating pipes occupying said shell, suitable saturate and superheated steam headers whereto the forward ends of said pipes are attached and a plurality of deflector plates provided arranged transversely within the shell, forming a tortuous passage therein, substantially as described. 90
5. The improvements herein described, comprising a locomotive fire-tube boiler, its fire box and smoke box, in combination with a shell having its rear end connected with the fire box by a plurality of short flues, the forward end of said shell opening through the front flue sheet of the boiler, a single casting containing alternate saturate and superheated steam passages and substantially closing the forward end of said shell, suitable walls within said smoke box further closing the same a damper for completely closing said forward end and a plurality of loop 95
6. A locomotive fire-tube boiler, its fire box and smoke box, in combination with a shell arranged within the boiler and connected with the fire box by a plurality of short flues, the forward end of said shell opening through the front flue sheet of the boiler and a plurality of vertical forwardly inclined alternated deflector plates arranged within said shell and provided with openings for superheater pipes, as and for the purpose described. 100
7. A locomotive fire-tube boiler, its fire box and smoke box, in combination with a corrugated cylindrical shell connected with the fire box by a plurality of short flues or tubes, said shell opening through the front flue sheet of the boiler, a plurality of saturate and superheated steam headers arranged in said smoke box and substantially closing the forward end of said shell, a plurality of loop pipes occupying said shell and connected with said headers and a plurality of deflectors in said shell, substantially as described. 105
8. The improvements herein described, comprising a metal casting containing a plurality of parallel vertical passages and also transverse passages connecting alternate parallel passages, to receive saturate and superheated steam respectively, and a plurality of loop pipes, each connected with a saturate steam passage and a superheated steam passage, substantially as described. 110
9. The improvements herein described, comprising a fire tube boiler, its fire box and smoke box, in combination with a shell extending through an opening in the front flue sheet of the boiler, a plurality of fire tubes connecting the rear end of said shell with the fire box, a superheater arranged in said shell and partially closing the front end thereof, saturate and superheated steam pipes connected with said superheater within said smoke box and a movable closure beneath said superheater for completely closing the forward end of said shell, substantially as described. 115
10. The improvements herein described, comprising a fire tube boiler having a smoke box and containing a tortuous passage, a superheater comprising suitable headers in said smoke box and loops in said passage, substantially as described. 120
11. In a steam superheater, a header comprising upright front and back walls, side walls, a plurality of vertical partitions forming a plurality of saturate steam spaces and a plurality of superheated steam spaces therein, a posterior transverse passage connecting the upper ends of the superheated steam spaces and an anterior chamber connecting the upper ends of the saturate steam spaces; said chamber and passage being provided with steam outlet and inlet connections respectively, substantially as described. 125

In testimony whereof, I have hereunto set my hand, this 31st day of October, 1906, in the presence of two subscribing witnesses.

HENRY H. VAUGHAN.
